UNITED STATES PATENT OFFICE.

GEORGE H. F. HOLY, OF PITTSBURGH, PENNSYLVANIA, ASSIGNOR TO WESTINGHOUSE ELECTRIC & MANUFACTURING COMPANY, A CORPORATION OF PENNSYLVANIA.

WEIGHT-EQUALIZATION DEVICE.

Application filed December 7, 1920. Serial No. 428,872.

To all whom it may concern:

Be it known that I, GEORGE H. F. HOLY, a citizen of the United States, and a resident of Pittsburgh, in the county of Allegheny and State of Pennsylvania, have invented a new and useful Improvement in Weight-Equalization Devices, of which the following is a specification.

My invention relates to transformers and 10 it has particular relation to weight-equalization devices therefor.

One of the objects of my invention is to provide a wheeled base for a transformer whereby the total weight of the same may 15 be uniformly distributed among a plurality of wheels or rollers and thus automatically accommodate itself to irregularities in the track.

Another object is to provide a device of 20 the character designated that will comprise relatively few parts, may be quickly and easily assembled and strong and rugged in structure.

Briefly stated, my invention comprises a 25 main-frame structure upon which the transformer is mounted. Additional frame members, each of which carries a plurality of wheels, are pivotally mounted upon the main-frame structure. The additional 30 wheel-carrying frames are thus independent and are separately movable about horizontal pivotal connections.

Heretofore, in structures of this type, the 35 wheels, usually four in number, were mounted directly upon the main transformer-supporting frame and were immovable, in a vertical direction, with respect to each other.

By means of my invention, each wheel may 40 move vertically with respect to any other wheel to accommodate itself to track irregularities or obstructions and, at the same time, to support its share of the load.

In the accompanying drawing,

Fig. 1 is a side elevational view of a transformer and a weight-equalization device constructed in accordance with my invention.

Fig. 2 is an end elevational view of the structure illustrated in Fig. 1.

Referring to the drawing, a transformer 1 is mounted upon a frame structure, preferably comprising a plurality of parallel spaced beams or channel bars 2 disposed in pairs adjacent to each side of the trans-

former. A plurality of trucks 3 are pivotally mounted, as at 4, between the beams 1 of each pair. Each of the trucks 3 preferably comprises a plurality of parallel frame elements 5 disposed in spaced and parallel relation and between which flanged wheels 6 are suitably mounted. Bearings 7 are provided in each of the side elements 5 of the trucks 3, for the axles of wheels 6, and may be of the ordinary railway journal type or provided with anti-friction elements. 55 60 65

By means of the structure shown and described, each truck may swing about its pivotal connection and between the channel bars 2 in a vertical plane to accommodate itself to irregularities of the track level and to 70 insure, at all times, an equal distribution of the weight of the transformer upon the wheels and track.

I claim as my invention:

1. The combination with a transformer, 75 of a main supporting frame comprising a plurality of pairs of spaced members, a plurality of wheel frames pivotally mounted between the members of each pair for independent pivotal movement with respect to 80 said frame.

2. The combination with a transformer, 85 of a main supporting frame comprising a plurality of pairs of spaced members, a plurality of wheel frames pivotally mounted between the members of each pair for vertical pivotal movement with respect to said frame.

3. The combination with a transformer, 90 of a main supporting frame comprising a plurality of pairs of spaced members, a plurality of supporting trucks pivotally mounted between the members of each pair for vertical pivotal movement with respect to said frame, said trucks comprising a plurality of spaced frame members having 95 wheels mounted therebetween.

4. The combination with a transformer-supporting frame, of a plurality of spaced frame members, a plurality of independent and separately movable wheeled trucks 100 pivotally mounted between certain of said members, said trucks each comprising a plurality of side members having wheels disposed therebetween.

In testimony whereof, I have hereunto 105 subscribed my name this 30th day of November, 1920.

GEORGE H. F. HOLY.
